UNITED STATES PATENT OFFICE

2,426,742

SCREW PROPELLER

Felix W. Pawlowski, Ann Arbor, Mich.

Application November 20, 1943, Serial No. 511,192

2 Claims. (Cl. 170—168)

1

This invention relates to propellers and more particularly to an improved propeller of the screw type.

One of the objects of the present invention is to provide a propeller having greater efficiency, or greater output of energy for a given input than it is possible to obtain with conventional screw propellers.

Another object of the present invention is to provide a propeller which can absorb and deliver greater power for its given diameter than can be absorbed and delivered by a conventional propeller of an equal diameter.

A further object of the present invention is to provide a screw propeller having greater rigidity and strength than conventional propellers of a corresponding description.

A still further object of the present invention is to provide an improved screw propeller with the aid of which it is possible to increase the cruising radius and the speed of various crafts, at the same power consumption or fuel supply as would be possible with a conventional propeller.

A still further object of the present invention is to provide an improved screw propeller having greater rigidity and strength.

A still further object of the present invention is to provide a more safe propeller less dangerous to persons who by accident may come close to the tips of the rotating blades.

It is an added object of the present invention to provide an improved screw propeller of the foregoing character which is simple in construction, dependable in operation, and is relatively inexpensive to manufacture.

Other objects and advantages of the present invention will be apparent from the following description and the appended drawings forming a part of the present specification, in which drawings similar numerals refer to similar parts throughout the several views.

Fig. 1 is a rear view of a screw propeller embodying the present invention.

Fig. 2 is a sectional view of the propeller of Fig. 1, said view taken in the direction of the arrows on the section planes passing through the broken line 2—2 of Fig. 1.

Fig. 3 is a view taken radially and inwardly on one of the blades of a propeller similar to the one shown in Figs. 1 and 2 but having a twisted blade.

Fig. 4 is a view similar in part to Fig. 3 and showing a blade of a different cross section.

Fig. 5 is a rear view of a modified screw propeller embodying the present invention.

Fig. 6 is a sectional view taken in the direction

2

of the arrows on the section plane passing through the section line 6—6 of Fig. 5.

Fig. 7 is a side view of one of the blades used in propellers embodying the present invention.

Fig. 8 is an end view, partly in section, of the blade shown in Fig. 7.

Fig. 9 is a side view of one of the blades of another type used in the propellers embodying the present invention.

Fig. 10 is an end view, partly in section, of the blade shown in Fig. 9.

Fig. 11 is a rear view of still another modified propeller embodying the present invention.

Fig. 12 is a sectional view taken in the direction of the arrows on line 12—12 of Fig. 11.

Before explaining in detail the present invention, it is to be understood that the invention is capable of other embodiments and modifications and that the terminology and phraseology employed herein is for the purpose of description and not of limitation, and it is not intended to limit the invention beyond the requirements of the prior art.

It is also to be understood that the term "screw propeller" as herein used refers to devices including a number of elements or blades so positioned with respect to their axis of rotation, that their rotation in a fluid medium, gas or liquid, produces a thrust in the direction perpendicular to the plane of rotation, which thrust is utilized to propel or move various crafts and other instrumentalities carrying such screw propellers. This term, as herein employed, does not refer to devices having different transformation of forces or energy, such, for instance, as devices in which the movement of liquid is utilized to develop rotative energy, such as water turbines. The term "streamline" as herein employed refers to "aerofoils" or shapes having well rounded leading edges and substantially sharp trailing edges, with connecting surfaces being straight, convex or concave.

In the drawings there are shown, by way of example, a number of screw propellers embodying the present invention. Referring particularly to the construction shown in Figs. 1 and 2, the construction illustrated therein comprises a substantially streamline hub 20 which is adapted to be drivingly connected in any suitable way to a driving shaft. To said hub 20 there are connected, in any suitable manner, a plurality, in the present instance three, of blades 21. The blades 21 have a streamline cross section which is substantially uniform throughout the effective length of the blades, the uniformity of the cross section

being maintained as much as considerations of strength of the blades and the necessity of reducing the tension due to centrifugal forces permits, particularly in larger and fast-rotating propellers. The blades 21 are set at a predetermined angle to the plane of their rotation, which angle may be either constant throughout the length of the blade, as shown in Fig. 2, or vary in any desirable manner, such as illustrated in Figs. 3 and 4.

To the outer extremities or tips of the blades 21 there are connected a plurality of substantially round plates 22 of streamline cross section, which plates are adapted to obstruct and thereby to eliminate in a material degree the objectionable flow of the fluid from the high pressure sides to the low pressure sides of said blades in operation of the propeller. By virtue of the above construction the loss of energy due to the above flow, which loss is usually referred to in the art as the "tip loss," is substantially eliminated and the efficiency of the propeller is greatly increased. By making plates 22 of streamline cross section, the resistance of the fluid to the motion of said plates 22 therethrough is greatly reduced, and the loss of energy due to it is brought to the point where it is greatly overbalanced by the gain due to the elimination of the tip losses.

Referring to the construction illustrated in Figs. 5 and 6, the screw propeller illustrated in said figures comprises a hub 30 which is similar to the hub 20 of the construction shown in Figs. 1 and 2. To said hub 30 there are connected, in any suitable manner, a plurality, in the present instance six, of blades 31. In this construction it is preferred to use more than four blades, six being one of the preferable numbers, although the use of higher number of blades, such, for instance, as ten or twelve may be still more desirable in certain instances. The ratio of the length to the width of the blade, in my improved propeller, is greater than 3 to 1, the ratio of 6 to 1 being one of the preferred ratios for average conditions, still greater ratios being desirable for special conditions. By decreasing the width and increasing the number of the blades a much greater efficiency of the propeller is attained.

The blades 31 are of streamline cross sections as shown in Fig. 8, the width of the blades being substantially uniform, as shown in Fig. 7. Under certain conditions it may be desirable to use blades with outwardly decreasing width, and to have the angle of each individual blade with respect to the plane of its rotation gradually changing along its length. It should be understood, however, that while in conventional propellers the width of a blade changes along the radius of a propeller rather abruptly, the width of a blade in my improved propeller changes very slightly, making both the leading and the trailing edges of a blade straight, or nearly straight lines, thereby eliminating considerable curvature which is common in many types of conventional propellers.

Means are provided to obstruct the flow of fluid from the high pressure sides to the low pressure sides of the blades. In the present embodiment of the invention said means are in the form of a circular rim 32 concentric with the hub and connected to the tips of the blades in any suitable manner. The rim 32 is of a streamline cross section, and its width should be sufficient to form a substantial obstruction to the tip flow of the fluid. It is preferable to have the rim of such a width that it overhangs the leading and the

trailing edges of the blades. By virtue of providing a continuous rim connecting the tips of all blades, the tip losses in the propeller are greatly reduced, and the structure of the propeller is made stronger.

For the proper understanding of the present invention, it is extremely important to understand that the rim 32 of my improved propeller is not a "shroud" or a conical ring, or blade tying hoop, many designs of which have heretofore been proposed in connection with screw propellers. While narrow hoops have been tried merely to strengthen propellers or to prevent flutter of the blades, various conical rings and shrouds have been proposed with the expectation that they would produce a compact column of fluid and would direct such a column of fluid at an increased speed against the propeller blade and would thus enable developing more power. However, in order to cause the fluid to converge toward the propeller blades, such shrouds cause separation of fluid from the opposite surface of the shroud, and the vacuum so produced causes serious drag on the propeller. Such drag is substantially equal to or is greater than the increase in the useful thrust of the propeller, and therefore no net increase in power is realized. In other words, the amount of power or energy which is spent for effecting such convergence of fluid toward the propeller blades is equal or greater than the amount of power or energy gained at the blades, and therefore no additional power or energy is thus gained by the use of such devices.

The rim 32 of my improved propeller is so designed as to have as little drag on the propeller as possible and it should not be made to perform the function of such a shroud, a conical ring, or a nozzle restricting the flow of fluid and forcing it at a higher speed into the propeller blades. The function of my rim is to obstruct the flow of fluid around the tips of the blades.

The provision of the rim encircling the blades and forming, in effect, a safety guard around them has an additional important advantage of making the propellers constructed in accordance with the present invention more safe, since it reduces greatly the danger to persons who by accident may come close to the tips of the rotating blades, such as people overboard or life-boats in cases of marine propellers, or parachutists and attending personnel in cases of aircraft propellers.

By staggering the blades either at their roots or at their tips, the strengthening function of the rim is greatly amplified. It is preferable to stagger the blades at their roots, and such a construction is shown in Figs. 11 and 12. Referring to said figures, said structure comprises an elongated, substantially streamline hub 40, a plurality of blades 41 connected to said hub, and a rim 42 connected to the tips of the blades 41. The construction and operation of this particular propeller, with the exception of the staggered arrangement of the blades and the resulting increased strength, is substantially similar to that of the construction illustrated in Figs. 5 and 6, and no further description of this propeller is deemed necessary.

There is thus provided an improved screw propeller, in which, by increasing the number of the blades and decreasing their width, by providing means for obstructing the flow of fluid around the tips of the blades, and by making the cross sections of the moving elements of streamline shape, the efficiency of the propeller, and its strength, are greatly increased, and the objects

of this invention, and a number of additional advantages are attained.

I claim:

1. In a thrust producing screw propeller, a plurality of blades in a number greater than four, in said blades the ratio of the length of the blade to its width being at least 6, each of said blades having a straight well rounded leading edge and a straight sharp trailing edge, the cross section of each of said blades being dimensionally uniform throughout the length of the blades, said blades being set to have uniform pitch throughout their lengths; and a circular rim encircling the tips of said blades and connected thereto, said rim having sufficient width to ensure its substantial overhanging both the leading and the trailing edges of the blades, said rim having its front edge well rounded and its rear edge sharp, the plane connecting the extreme lines of said rim edges around the entire rim forming a cylindrical plane 20 co-axial with the propeller.

2. A construction as defined in the preceding claim 1, the blades being made of rolled stock.

FELIX W. PAWLOWSKI.
